ICE MAKING UNIT

Raymond G. Hilger, Chicago, Ill.

Application March 21, 1955, Serial No. 495,408

3 Claims. (Cl. 62—107)

The invention relates to refrigerating units generally and more particularly to units of the type adapted for direct contact with liquid or gaseous substances to be chilled.

One object of the invention is to provide a refrigerating unit of the above general character constructed and arranged for efficient application of either a liquid or gaseous defrosting medium whereby the unit may be quickly cleared of accumulations of frost or ice and in which the defrosting medium is effectively segregated from the refrigerant and from the substance being chilled by the unit.

Another object is to provide a refrigerating unit which, considering its size, presents an exceptionally large effective area for quickly and efficiently producing sheets or slabs of ice and in which the surfaces of such areas are smoothly finished and oriented so that the accumulated ice can slide or fall off freely when loosened by a momentary application of heat to the unit.

A further object is to provide an efficient, light weight refrigerating unit that is simple yet rugged and durable, that can be fabricated from chilling elements that are commercially available and relatively inexpensive, all of which contribute to the low cost of production of the unit.

Other objects and advantages of the invention will become apparent from the following detailed description of the preferred embodiment illustrated in the accompanying drawing, in which:

Figure 1 is a perspective view of a refrigerating unit embodying the features of the invention.

Fig. 2 is an exploded perspective view of the unit showing the configuration of the various parts and the manner in which they are assembled and interrelated to form a complete unit.

Fig. 3 is a sectional view through the unit taken in a vertical plane substantially on the line 3—3 of Fig. 1.

While a single preferred embodiment of the invention has been shown and will be described herein, it is to be understood that this detailed disclosure is not intended to limit the invention to the specific construction shown. On the contrary, the intention is to cover all modifications and alternative constructions falling within the spirit and scope of the invention as expressed in the appended claims.

The improved cooling unit in its preferred form as shown in Fig. 1 comprises a hollow, box-like sheet metal structure 5 which is generally trapezoidal in vertical transverse cross-section. More particularly, the unit has two flat side walls 6 and 7 of relatively large area, relatively closely spaced at their upper edges and joined together by a V-shaped top member 8. The side wall members diverge outwardly toward their lower edges which are joined by an inverted V-shaped bottom member 9. End wall members 10 and 11 (Fig. 2) welded or otherwise joined to the side, top and bottom members close the opposite ends of the structure to form a liquid-tight chamber.

Intimately associated with the inner face of each of the side wall members 6 and 8 is a coil, or the like,

2

defining a continuous refrigerant circulating channel 12 of substantial length. The channel 12, as shown, zig-zags back and forth across the side wall member from the top toward the bottom edge and has an inlet 13 at one end and an outlet 14 at the other end. As herein shown, the inlet and outlet are located at opposite ends of the unit with the inlet adjacent the top and the outlet adjacent the bottom. It will be understood of course that other forms of channeling may be employed, if desired.

A refrigerant, such as liquid ammonia, Freon, or chilled brine circulating through the channels 12 quickly lowers the temperature of the side wall members for cooling liquids or gases in contact with their outer faces. The location of the coils on the inner faces of the side wall members makes it possible to finish the outer faces with a smooth surface from which accumulations of ice or frost can be easily freed by application of a relatively small amount of heat to the inner faces of the members.

With the particular shaping of the unit shown, the side wall members are disposed in a generally upright position, slightly inclined to the vertical so that the ice or frost accumulations will slide off cleanly when loosened by a slight increase in the temperature of the wall members.

The improved unit is particularly well adapted for defrosting by the use of the heated liquids or gases readily available in refrigerating systems. The liquid or gaseous defrosting medium is simply introduced into the chamber provided between the side wall members while the circulation of refrigerant through the channels 12 is temporarily interrupted. For this purpose suitable ports 15 and 16 are provided in one of the end members, in this instance, the end member 11 (Fig. 2) for introducing and withdrawing the defrosting medium.

To produce a unit of high efficiency and yet maintain manufacturing costs low, I prefer to utilize as side wall members commercially available cooling plates with the refrigerant channels 12 formed directly therein. Such plates, commonly known in the art as "platecoils," are made up of two metal sheets, one of which is formed with a groove of serpentine or other suitable configuration for defining the continuous refrigerant passage or channel 12. The other sheet is assembled in overlying relation to the first sheet to close the open side of the groove, and the sheets are rigidly and permanently joined together by welding, brazing, or otherwise.

As shown in Fig. 2, the side wall members, whether "platecoils" or other comparable cooling plates, are generally rectangular in form and dimensioned to present a heat exchange surface of substantial area. While the upper edges of the two members may be welded together, if desired, I have found it preferable to join them by means of a V-shaped top member 8. This may be a simple sheet metal stamping of the same length as the side wall members and having its legs dimensioned and bent to overlap the upper edges of the wall members for welding or brazing thereto so as to provide a fluid-tight joint.

As the side wall members diverge toward their lower edges, the bottom member 9 is made substantially wider than the top member 8. Preferably, this bottom member is a V-shaped metal stamping formed with indent flanges 17 along the upper edge of each leg. These flanges may be telescoped between the side members 6 and 7 and welded or brazed to the lower edges of the members. It will be apparent that the side, top and bottom members when assembled in the above manner define a hollow box of trapezoidal section in a vertical plane.

The end members 10 and 11 which close the ends of the chamber are simple sheet metal stampings shaped to overlie the ends of the companion members to which they are attached by welding or brazing. To provide

access to the ports 13 and 14 of the refrigerant channels 12, the end members are apertured for the reception of nipples 18 and 19 respectively inserted in the ports 13 and 14 and welded or brazed to the adjacent channel-forming structure.

In the particular unit illustrated, end member 10 is formed with apertures 20 for accommodating the nipples 19 leading from the outlet ports 14 of the respective side wall members. Similarly, end member 11 is formed with apertures 21 for accommodating the nipples 18 leading from the inlet ports 13. Suitable gaskets of packing may be provided between the nipples and the end members to prevent leakage, or alternatively, the nipples may be welded or brazed to the end members. Nipples 22 and 23 inserted in the ports 15 and 16 and welded to the member 11 provided for convenient attachment to the refrigerating system for circulating defrosting medium through the interior of the unit.

When installed in a refrigerating system, two cooling plates of the unit may be connected in parallel. Thus the nipples 18 for the refrigerant channel inlets are connected by elbows 24, short lengths of tubing 25, and a T-fitting 26 with a refrigerant supply conduit 27. Similarly, the nipples 19 for the channel outlets 14 are connected by elbows 28, short lengths of tubing 29, and a T-fitting 30 to the suction line 31 of the refrigerating system.

The unique shape of the cooling unit makes it particularly suitable for freezing thin sheets or cakes of ice or for cooling liquids by direct contact. The liquid to be frozen or chilled is directed over both cooling plates in a thin uniform film by a suitable header 32 adjacent the upper end of the unit. This header may conveniently comprise a piece of pipe or tubing split longitudinally along one side as at 33 and spread apart so as to straddle the V-shaped top member 8 of the unit as shown in Fig. 1. To provide an outlet of uniform cross-sectional area from the header, the edges may be formed with spaced projections 34 adapted to bear against the top member. It will be understood, of course, that one end of the header is closed while the other is connected by suitable piping with the liquid circulating system.

It will be apparent from the foregoing that the invention provides a refrigerating unit of novel and advantageous construction, particularly suitable for chilling liquids and gases by direct contact. Thin sheets or slabs of ice may be quickly and efficiently produced by the unit and removal of the sheet of ice or frost accumulations on the side plates is effected quickly by a momentary application of a liquid or gaseous defrosting medium. Since

the improved unit effectively segregates the defrosting medium from the refrigerant and from the substance being chilled, heated water or hot gases readily available in refrigerating systems can be conveniently used for defrosting purposes.

I claim as my invention:

1. A refrigerating unit comprising, in combination, a pair of sheet metal side wall members of substantial area disposed in oppositely inclined intersecting planes, means defining a continuous channel intimately and continuously associated with the inner face of each member and disposed so as to chill the entire surface of the member sufficiently to form ice on its outer face when a refrigerant is circulated through the channel, top, bottom and end members assembled with and joined to said side members to define a liquid-tight chamber between the side members completely isolated from said channel, said top and bottom members comprising V-shaped metal stampings having their edge portions joining the respective upper and lower edge portions of the side members in a continuous liquid-tight joint, a header supported adjacent the top member for directing liquid to be cooled over the side wall members in a relatively thin film, one of said end members having inlet and outlet ports communicating with said chamber for introducing and withdrawing therefrom a fluid defrosting medium effective to raise the temperature of the members above the freezing point, said side wall members presenting smooth, steeply sloping outer faces from which accumulated ice can fall freely upon introduction of the defrosting medium to said chamber.

2. A refrigerating unit as defined in claim 1 in which each of the side wall members comprises a pair of relatively thin metal sheets secured together in face-to-face relation, one of said sheets being suitably grooved to define the refrigerant channel.

3. A refrigerating unit as defined in claim 1 in which one of the end members is apertured to provide for connection of the ends of the refrigerant channel with a refrigerant circulating system.
